No. 884,588.

PATENTED APR. 14, 1908.

W. M. JAMESON.
DEVICE FOR FORMING WIRE HAT FRAMES.
APPLICATION FILED MAR. 17, 1906.

UNITED STATES PATENT OFFICE.

WINTHROP M. JAMESON, OF CAMBRIDGE, MASSACHUSETTS.

DEVICE FOR FORMING WIRE HAT-FRAMES.

No. 884,588.

Specification of Letters Patent.

Patented April 14, 1908.

Application filed March 17, 1906. Serial No. 306,496.

To all whom it may concern:

Be it known that I, WINTHROP M. JAMESON, a citizen of the United States, and a resident of Cambridge, in the county of Middlesex and State of Massachusetts, have invented an Improvement in Devices for Forming Wire Hat-Frames, of which the following description, in connection with the accompanying drawing, is a specification, like letters on the drawings representing like parts.

This invention has for its object the production of a device for forming wire hat frames for ladies' hats, and in particular frames of this class made up of a series of round-and-round wires, and a series of fore-and-aft wires radiating from a common center, and attached to the round-and-round wires by being twisted around them. Hat frames of this character are made up in various regular and irregular shapes with circular, elongated, flat, indented and straight or bell crowns, and with brims and coronets varying in shape according to the design. It is essential in devices for forming these frames that the wire supporting members shall be capable of adjustment to produce all these various forms of frames, and further, that when the frame is formed and completed that the wire supporting members may be moved to permit the removal of the completed frame without disturbing their adjustment, so that when the device is once set in position for any given design, any desired number of hat frames may be formed thereon.

The present invention discloses a device which responds to all these requirements of a successful device for forming wire hat frames, and which is extremely simple and strong in its construction.

The leading features of the invention will be seen from the accompanying specification and will be particularly pointed out in the appended claims.

In the drawings, Figure 1 represents a side elevation, partly in cross-section, of the device showing the wire supporting members in position along the line of one of the fore-and-aft wires; Fig. 2 is a view similar to Fig. 1 showing but a part of the device and showing the wire supporting members arranged in a slightly different way to secure the same result; Fig. 3 is a top plan view of the device as shown in Fig. 1, only two sets of wire supporting members being shown in position;

Fig. 4 is a detail partially in cross-section of the device to show the construction and operation of the clamping means for each wire supporting member.

The device comprises a suitable standard or support A, which may be of any desired form and height, and may rest upon or be secured to the floor or a suitable bench or table. Supported upon the standard or support are a series of substantially radially-arranged vertical guides B for the wire supporting members. In the preferred form of the device illustrated and for convenience of manufacture these guides are cast integral with a base made in two parts C and D. The guides B are preferably slotted throughout their length to provide for the support and adjustment of the wire supporting members.

Each guide B is provided with a series of wire supporting members in the form preferably of straight, round rods E, provided at the upper end with a recess or notch, herein shown as of annular form for receiving and holding the round-and-round wires of the frame.

Each wire supporting member is adjusted and held in position against the flat, vertical side of the guide B by means of a clamping bolt F which passes through the slot in the guide and surrounds or grasps the wire supporting member. A suitable fastening means, such as a nut G, threaded on the end of the bolt F acts to hold and lock each member E in its adjusted position by drawing it tightly against the vertical face of its guide B.

It will thus be seen that each wire supporting member may be adjusted radially of the device and the frame to be formed by moving the clamping bolt F longitudinally of the guide B in the slot, that it may be adjusted vertically by moving it up and down in the clamping bolt, and that it may be adjusted angularly by swinging the clamping bolt in the slot of the guide B. This individual attachment of each wire supporting member to the guide, and this variety and facility of adjustment enables the various wire supporting members to be set into any desired form for a hat frame.

The device is shown adjusted in two ways in Figs. 1 and 2. In Fig. 1 those wire supporting members used to support the round-and-round crown wire are shown as provided with a series of notches e, so that if the point where a round-and-round head wire or

a round-and-round frame wire should be, or happen to fall, directly below the point for the round-and-round crown wire, and it should be desirable to maintain the wire supporting members vertical, then one of these notches *e* could be used to support such round-and-round head or frame wire. In Fig. 2 the device is shown as set up for a similar frame as shown in Fig. 1, but without making use of any notches *e* and by simply adjusting in an angular direction the wire supporting members.

The number of wire supporting members is not fixed, and it depends upon the range of frames to be made upon a given device. I have shown different numbers in Figs. 1 and 2, and I have also shown in Fig. 1 a different number for the rear portion of the frame from that for the front portion.

After the wire supporting members have once been set in position, any number of wire frames may be formed thereon in the usual way, that is, by winding wires round-and-round, as indicated at *a* for the brim wires, at *b* for the head wire, and at *c* for the crown wire. The fore-and-aft wires, one only of which is indicated in dotted lines at *d*, are then put in position by being twisted about the round-and-round wires close to the side of the wire supporting members.

When the wire brim is completed it is essential that it be removed from the device without disturbing the adjusted position of the wire supporting members. To secure this end it is necessary to contract the figure formed by the ends of the wire supporting members to such an extent as to free the hat frame therefrom and allow its removal, or in other words, to change the position of a plurality of the guides to which the wire supporting members are rigidly held in their adjusted positions by the clamping bolts. This result is secured in the preferred form of my invention by making the base upon which the guides are formed in two parts *C* and *D*, one part, as *C*, being attached fast to the support or standard *A*, as by screws *G*, and the other part as *D* being hinged to the fixed part *C*, as shown at *H*. In this construction after the hat frame has been formed the plurality of guides carried by the movable part *D* of the base are swung upwardly and inwardly, thus carrying with them a plurality of series of wire supporting members, so that the upper ends of the various wire supporting members are brought towards one another and the figure formed by the ends of said members is contracted to allow the removal of the hat frame but without in any way disturbing the position of any wire supporting member with respect to its guide.

The particular construction of the base *C*, *D*, is immaterial, although it is here shown as a web extending from one slotted guide to the other, and provided with slots

K close to the front vertical faces of each guide to allow the passage of wire supporting members. In this form it adds weight to the structure and tends to hold the device in suitable position, but any form of construction whereby the radial guides may be supported from the standard and a plurality of them moved to contract the figure formed by the ends of the wire supporting members without disturbing the adjusted relation of the wire supporting members to their respective guides is within the scope of this invention.

Having described my invention, what I claim as new and desire to secure by Letters Patent, is:-

1. A device for forming wire hat frames, comprising a support or standard, radially arranged, longitudinally slotted guides supported thereby, a series of wire supporting members for each guide, individual clamping means for attaching each member to its slotted guide permitting vertical and lateral adjustment of each member on its guide, means permitting the figure formed by the ends of said members to be contracted without disturbing their adjusted relations to their respective guides.

2. A device for forming wire hat frames, comprising a support or standard, radially arranged, longitudinally slotted guides supported thereby, a series of wire supporting members for each guide, individual clamping means for attaching each member to its slotted guide, permitting vertical, angular and lateral adjustment of each member on its guide, means permitting the figure formed by the ends of said members to be contracted without disturbing their adjusted relations to their respective guides.

3. A device for forming wire hat frames, comprising a support or standard, radially arranged longitudinally slotted guides supported thereby, a series of wire supporting members for each guide, individual clamping means for attaching each member to its slotted guide, permitting a vertical and lateral adjustment of each member on its guide, means permitting the position of a plurality of the guides relatively to their support to be changed to allow the removal of the completed frame without disturbing the adjusted position of the members on their respective guides.

4. A device for forming wire hat frames, comprising a support or standard, radially arranged longitudinally slotted guides supported thereby, a series of wire supporting members for each guide, individual clamping means for attaching each member to its slotted guide, permitting a vertical, angular and lateral adjustment of each member on its guide, means permitting the position of a plurality of the guides relatively to their support to be changed to allow the removal of

- the completed frame without disturbing the adjusted position of the members on their respective guides.
5. In a device for forming wire hat frames, 5 radially arranged, vertically faced guides, a series of wire supporting members for each guide, individual means for clamping each member against the vertical face of its guide.
- 10 6. In a device for forming wire hat frames, radially arranged, vertically faced guides, a series of wire supporting members for each guide, a separate clamping bolt for each member passing through the guide and acting to lock the member against the guide, whereby it may be held in any desired position of adjustment.
- 15 7. In a device for forming wire hat frames, radially arranged, longitudinally slotted, 20 vertically faced guides, a series of wire supporting members for each guide, a separate clamping bolt for each member passing
- through the slot in the guide and acting to lock the member against the guide, whereby it may be held in any desired position of vertical, angular or lateral adjustment. 25
8. In a device for forming wire hat frames, radially arranged, longitudinally slotted, vertically faced guides, a series of wire supporting members for each guide, a separate 30 clamping bolt for each member passing through the slot and embracing the member, and acting to lock the member against the vertical face of the guide in any desired position of vertical, angular or lateral adjustment. 35

In testimony whereof, I have signed my name to this specification, in the presence of two subscribing witnesses.

WINTHROP M. JAMESON.
